United States Patent Office.

ORLANDO M. HIGGINS, OF LOWELL, MASSACHUSETTS, ASSIGNOR TO HIMSELF AND FREEMAN HIGGINS, OF MANCHESTER, NEW HAMPSHIRE.

Letters Patent No. 72,718, dated January 28, 1868.

IMPROVEMENT IN STOVE-PIPE COUPLING.

The Schedule referred to in these Letters Patent and making part of the same.

TO ALL WHOM IT MAY CONCERN:

Be it known that I, ORLANDO M. HIGGINS, of Lowell, in the county of Middlesex, and State of Massachusetts, have invented certain new and useful Improvements in Stove-Pipe Couplings and Heaters combined, of which the following is a full, clear, and exact description, reference being had to the accompanying drawings, making part of this specification, in which—

Figure 1 is a vertical sectional elevation of my invention as applied to a stove, and between a stove and a chimney.

Figure 2, a side view, with the end of one of the connecting-pipes, which connect with the stove or with the chimney.

Figure 3, a transverse vertical section on the line A B of fig. 1, but with both of the fly-dampers closed.

Figure 4 is a top view.

This invention consists, first, in an adjustable endless metal band, *a*, arranged between heads or end-pieces *b*, which have semicircular projections *d* upon their inner sides, and near the rounded top and bottom ends thereof, and flanges *f* projecting inward from each edge between the rounded ends. The projections *d* hold the endless metal band outward to a form corresponding with the rounded top and bottom ends of the heads *b*, and the flanges *f* hold the endless metal band in and straight with the vertical sides of the heads or end-pieces. Connected with the thin endless metal band, and at each side thereof, are coupling or connecting-tubes *A*, projecting outward in opposite directions. Either one of these coupling-tubes may connect with the stove *B*, and the other coupling-tube with the chimney *C*, in the usual way.

The principal object of this endless band-coupling is to provide easy, convenient, and available means of connecting stoves with chimneys where the outlet of the stove is a little or much higher or lower than the stove-pipe hole or connecting-aperture in the chimney, or to couple or connect stove-pipes or other smoke or heat-conductors which do not come in a line with each other. In setting up a stove, or in changing a stove from one room to another, there is almost invariably found a difference of from one-half of an inch to four inches or more between the height of the outlet of the stove and the connecting-aperture in the chimney. This discrepancy is generally overcome by a suitable elbow, which has to be made expressly for the occasion, and a new elbow is necessary almost every time a stove is set up in a new place, or in a room where such stove has not been set up before; consequently, the changing of a stove from one room to another, or from one house to another, is almost always attended with the expense of from one to five dollars for a new elbow, or some other and more costly connection.

In the use of my improved adjustable endless-band stove-pipe coupling and heater, the thin metal band can be easily and conveniently moved to bring either of the connecting or coupling-tubes *A* to the right position and height to enter the aperture in the chimney, and the other coupling-tube on the opposite side of the endless band to the right height to couple on to the connecting-ring *c*, projecting from the side, *D*, of the stove, all as clearly shown in fig. 1.

When the relative position of the coupling-tubes *A* is to be changed, two screws, *g*, which pass through one of the end-pieces, *b*, into the central partition *E*, are slackened from one-half to a whole turn, which relieves the endless band *a*, when, by holding the case firmly, the endless band may be easily moved, in either direction, along the straight sides and around the ends of the heads *b*, to bring the coupling-tubes into the desired position to connect the stove with the chimney, whether the outlet of the stove is higher or lower than the aperture in the chimney. After adjusting the coupling-tubes, the screws *g* are tightened, and the parts are firmly held in position.

When the aperture in the chimney is the same height of the outlet of the stove, a straight pipe is generally employed, and when the aperture in the chimney is a little higher than the outlet of the stove, the latter may be elevated by placing blocks under the feet of the stove-legs. It is much better, however, to keep the stove as near the floor as convenient, in order to obtain the best results from the fuel consumed, or the effect of radiated heat near the floor. When the aperture in the chimney is lower than the outlet of the stove, it is more difficult

to connect such stove with the chimney. The stove cannot be lowered, nor can the chimney be elevated, and an offset-coupling is a matter of necessity.

My invention and improvements are admirably adapted to either of the above-described conditions or circumstances, as the coupling-tubes can be as readily set in one position as in another—either both coupling-tubes on a line with each other, or either higher than the other—and, by making the heads *b* and the endless band long enough, any reasonable amount of variation in the height of the coupling-tubes can be had.

The central partition *E* is generally cast in one with one of the heads *b*, and the opposite head is secured to the partition by screws *g*, as before stated, and shown in figs. 2 and 3.

Above the top end of the partition, and below the lower end thereof, are fly-dampers *F*, to regulate the draught or current of air from the stove to the chimney, and, as will be seen, either of these dampers may be turned so as to throw the current of air and the smoke in either direction. In the present instance, shown in fig. 1, the top damper is closed, and the lower damper is opened, to allow smoke to pass downward and outward, as indicated by arrows.

To the top of the case, which may be either end up, I apply a perforated disk, *m*, upon which articles may be placed to heat, or a vessel, to heat the contents, as for heating tea or coffee, or a pie. Through each or either of the heads, *b*, I provide one or more holes, *h*, to admit cold air to the case or heater, and a movable slide, *k*, having corresponding holes, is arranged to cover or uncover said air-holes, the object of which is to regulate or measurably control the draught of air through the stove to the chimney. The perforated disk may be readily removed from the top of the case or heater, and as readily replaced thereon.

My invention and improvements not only serve as a cheap and convenient coupling for stoves, as described, having ample range of adjustment to accommodate almost any stove or chimney, but they serve as an economical heater or heat-saving device, to radiate into the room much of the heat that would otherwise pass off to the chimney.

What I claim as new, and desire to secure by Letters Patent, is—

1. The endless metal band *a* and coupling-tubes *A*, combined with the heads *b*, for the purpose, and substantially as described.
2. The heads *b*, constructed as described, whereby the endless metal band may be adjusted, substantially as set forth.
3. The partition *E* and screws *g*, combined with the heads *b* and endless band *a*, as and for the purpose set forth.
4. The dampers *F*, combined with the partition *E*, heads *b*, and endless band *a*, in the manner and for the purpose substantially as described.
5. In combination with the head *b*, the slide *k* and holes *h*, for the purpose and substantially as described.
6. The perforated movable disk or stand *m*, applied to the top of the case or heater, as and for the purpose described.
7. The combination of all the correspondent parts specified, arranged for action and effect substantially as described, and for the purposes specified.

ORLANDO M. HIGGINS.
